DISH OR SIMILAR ARTICLE

George A. Baker, Walnut Park, Calif., assignor to Max Weil

Application February 6, 1951, Serial No. 14,119

Term of patent 3½ years

(Cl. D44—15)

To all whom it may concern:

Be it known that I, George A. Baker, a citizen of the United States of America, residing at Walnut Park, California, in the county of Los Angeles and the State of California, have invented a new, original, and ornamental Design for a Dish or Similar Article, of which the following is a specification, reference being had to the accompanying drawing, forming part thereof.

The figure is a plan view of a dish, showing my new design. The dominant features of my design reside in the portions shown in full lines.

I claim:

The ornamental design for a dish or similar article, as shown and described.

GEORGE A. BAKER.
